UNITED STATES PATENT OFFICE.

ALOYS WIRSCHING, OF BROOKLYN, NEW YORK.

PRINTING-TELEGRAPH.

SPECIFICATION forming part of Letters Patent No. 286,667, dated October 16, 1883.

Application filed June 11, 1883. (No model.)

To all whom it may concern:

Be it known that I, ALOYS WIRSCHING, of Brooklyn, in the county of Kings and State of New York, have invented certain new and 5 useful Improvements in Printing-Telegraph Instruments; and I do hereby declare that the following is a full and exact description thereof.

This invention relates more particularly to 10 that class of instruments in which two type-wheels are employed, impressions from either of which may be produced at the will of the operator at the transmitting-station. Certain parts of the invention may, however, be used 15 advantageously in connection with instruments having but one type-wheel.

In a patent granted to me October 3, 1882, No. 265,353, I have described a printing-telegraph instrument in which a single polarized 20 armature of a horseshoe electro-magnet is employed to control, by means of an escapement, the rotation of the type-wheel. According to the present invention, I employ for this purpose two electro-magnets, preferably of the horseshoe type, and a double polarized armature, so arranged on a permanent horseshoe-magnet that one member of said armature is constantly charged by the north pole of the permanent magnet, while the other is constantly charged 25 by the south pole thereof. The two electro-magnets operating this double armature are so arranged that one pole of each co-operates with one of the two members of the armature while the other poles of said electro-magnets 30 co-operate with the second member of the armature. These escapement electro-magnets are simultaneously energized by a rapid succession of alternating electric impulses of opposite polarity transmitted over the line-wire 35 from a suitable transmitting-instrument, and the double armature carries a single pallet, which engages with the teeth of the escapement-wheel, said teeth being arranged in two concentric rows. The printing is effected by 40 means of a separate magnet, the armature of which is fixed upon the axis of the printing-lever. Both the escapement-magnets and the printing-magnet are actuated by the same current transmitted over the line-wire; but the 45 printing-magnet is arranged in multiple arc with relation to the two escapement-magnets, the latter being considered as a unit, while

these escapement-magnets, considered separately, are arranged in series in the split circuit of the instrument. The resistance of the 55 escapement-magnets is larger than that of the printing-magnet, and consequently the latter is not affected sufficiently to operate the printing-lever so long as the rapid succession of alternating electric impulses of opposite polarity continues to be received by the instrument, while the escapement electro-magnets are affected to a sufficient extent to operate 60 their double armature, and consequently the escapement; but as soon as an impulse of either 65 polarity is allowed to continue for a longer period, the printing electro-magnet becomes sufficiently charged to attract its armature, and consequently raise the printing-lever; and in order now to obtain all the available power 70 from the current for effecting the printing, I arrange, in connection with the printing mechanism, a circuit-breaking device, which, after the type-wheel has arrived in the desired position, and as soon as the printing-lever has 75 begun its movement, breaks the circuit in that branch of the instrument which contains the escapement electro-magnets, so that then the entire current transmitted over the line is thrown upon the printing-magnet, thus increasing 80 the power thereof, and consequently the force with which the impression-pad is pressed against the type-wheel. On the return of the printing-lever to its original position the circuit in the branch of the escapement-magnets is again closed and the operation 85 of the instrument continues. The arrangement of the escapement-magnets with relation to the printing-magnet, as described, offers another important advantage. It will 90 be noticed that the two branches, containing the one the escapement-magnets and the other the printing-magnet, constitute a close circuit within the instrument, and since, as above stated, the escapement-magnets offer considerable electrical 95 resistance, the induced current or discharge in the opposite direction from these electro-magnets, which occurs at every interruption and reversal of the current transmitted over the line, becomes effective in rapidly releasing 100 the double armature and helping the subsequent impulse from the line, which is in the same direction as the local discharge, to cause the oscillation of the armature, allowing the

escapement-wheel to make another step. The escapement-wheel arbor carries two type-wheels, mounted at a short distance from each other, and in order to effect the printing from either type-wheel at will, I employ a double-impression pad, each part being formed with alternating impression-surfaces and hollow spaces, so arranged that the impression-surfaces of one part come opposite the hollow spaces of the other part. This double-impression pad is capable of revolving in one direction with a step-by-step motion, at the will of the operator at the transmitting-station, according as he desires the impressions to be taken from one type-wheel or the other. The mechanism for effecting this is simple, there being arranged two ratchet-wheels corresponding to the two parts of the impression-pad, and two pawls, either of which is thrown into position at given positions of the escapement-arbor, to operate upon its ratchet-wheel when the latter is brought in contact therewith by the operation of the printing-lever.

Certain minor details of the invention will be referred to further on.

The accompanying drawings form a part of this specification, and represent what I consider the best means of carrying out the invention.

Figure 1 is a plan view of my improved instrument. Fig. 2 is a front elevation thereof. Fig. 3 is a section on the line $x-x$, Fig. 1. Fig. 4 is a section on the line $y-y$, Fig. 1. Fig. 5 is a plan of a portion of the escapement-wheel and its controlling-pallet. Figs. 6 and 7 are sections on the line $z-z$, Fig. 5, showing the parts in two different positions. Figs. 8, 9, and 10 are elevations, partly in section, of some of the parts shown in Fig. 2, said parts being represented on an enlarged scale in different positions. Figs. 11 and 12 are diagrams. Fig. 13 shows a portion of a strip of paper printed on my instrument. Fig. 14 shows a modification of certain parts.

Similar letters of reference indicate corresponding parts in all the figures.

A is the fixed frame-work.

B is the escapement-wheel arbor, driven in any suitable manner—for instance, by a train of clock-work actuated by a weight suspended on a cord running over a drum, as represented at the left of Figs. 1 and 3.

C and D are two horseshoe electro-magnets. E is a permanent horseshoe-magnet, arranged between C and D, and to the poles of which are pivoted the pieces F and G, these latter being connected with each other by means of a bridge of non-magnetic material, and constituting therewith what I call the "double polarized armature." The parts are so arranged that the piece F is influenced by the pole c of the magnet C, and also by the pole d of the magnet D, while the piece G is influenced by the poles c' and d' of said magnets.

H is the printing electro-magnet, the armature H' of which is fixed upon the axis i of the printing-lever I. The latter, when at rest,

bears against a contact-point 1, which is insulated from the metallic framing A. The line-wire 2 is connected to the binding-post a . From the latter one connection, 3, leads to the magnet H, and from this magnet the connection 4 leads to the binding-post a' , from whence the current passes either to the ground or over another line-wire to a second instrument. From the binding-post a another connection, 5, leads to magnet C. From C the current passes through 6 to magnet D. From the latter it passes through 7 to the metallic framing A and printing-lever I, and from I through 1 and 8 to binding-post a' . The magnets C and D are so wound that when c becomes north pole and c' south pole d will become south pole and d' north pole, and when c becomes south pole and c' north pole d will become north pole and d' south pole.

Referring to the diagrams Figs. 11 and 12, supposing the end of the permanent magnet E between the poles c and d to be the north pole of said magnet, then the part F of the double armature will constantly be charged by the north pole, and the part G will be charged by the south pole of said permanent magnet. Now, if an electric impulse of such polarity is sent over the line as will make c and d' north poles and c' and d south poles, then the right-hand ends of the pieces F and G will both be attracted and the left-hand ends will be repelled. When, then, that impulse is interrupted, the local induced discharge from the coils of the magnets C and D will reverse the polarity of said magnets, and thus come in aid to the subsequent impulse of opposite polarity to the first transmitted over the line, whereby the rapid oscillation of the double armature is effected. The efficiency of this induced discharge from the coils of the magnets C and D is increased by the fact that the conductors a 3 H 4 a' 8 1 I A 7 D 6 C 5 constitute a closed circuit. When an electric impulse of positive or negative polarity is allowed to pass over the line for a sufficient length of time to charge the magnet H, so that the latter attracts its armature H' and raises the printing-lever I, then immediately after such motion has commenced the contact at 1 is broken and the entire quantity of the current is compelled to flow from a , through 3, H, and 4, to a' , thus increasing the power of the magnet H and effecting the printing in a more reliable manner. The printing-lever I is depressed to its position of rest by a spring, I', which, on its upward movement, it has to deflect. This spring I' is formed with a hook, i' , that engages with a pin, i'' , so as to arrest the spring just before the lever I reaches its position of rest and makes contact at 1. The result of this arrangement is that at the beginning of the upward motion of the printing-lever, while the current still traverses both branches of the split circuit within the instrument, the only resistance offered to the motion of the lever I is its own gravity, and that this resistance is increased by the downward pressure of the spring I' only after the force of the

magnet H has increased by the breaking of the contact at 1 and the resulting exclusion of the branch containing the magnets C and D. The gravity of the printing-lever I and its connected parts, after it has acquired the momentum due to the pressure of the spring I', is sufficient to return it from the point where it ceases to be influenced by the spring I' into contact with the point 1.

10 One advantage heretofore not mentioned of the arrangement of the two horseshoe electro-magnets C and D and the double polarized armature F G consists in the fact that the permanent magnet E is always maintained at the degree of saturation to which it has been originally charged, for while, in the ordinary single polarized armatures, the magnetic circuit of the armature-carrying magnet can of course never be closed, so that the magnet 15 gradually loses its power, in my instrument, while not in operation, the magnetic circuit is constantly closed, and while in operation said circuit becomes closed at every oscillation of the armature. This magnetic circuit is established from the poles of the magnet E through the plates F and G and the cores of one or the other of the electro-magnets C or D, on which the plates F and G happen to rest for the time being.

20 The escapement-wheel B' upon the arbor B is formed with two concentric rows of laterally-projecting teeth, b and b', which engage alternately with the pallet b², projecting from an arm, b³, of the bridge-piece uniting the parts 25 F and G of the double polarized armature. The operation of these parts will be fully understood on inspection of Figs. 5, 6, and 7 of the drawings. The combination of the single pallet b³, the arm b³ of which is adjustable longitudinally, and may also be adjusted vertically by simply bending it slightly, constitutes a great advantage in the manufacture, as the teeth upon the wheel can be spaced and finished with great exactness, and with the 40 utmost facility, without any special reference to the position of the single pallet, which may be subsequently adjusted in mounting the instrument so as to properly co-operate with said teeth.

45 The type-wheels J' and J² are rigidly mounted upon the shaft B, as shown. For telegraphing stock quotations, &c., I propose to form one wheel, J', with letters only and the other wheel, J², with numerals and fractions; but I do not confine myself to such particular arrangement. These wheels should be so mounted that the characters of one are exactly, or nearly so, opposite those of the other, as shown, so that when the arbor B is arrested 55 for an impression such impression would be taken from both wheels simultaneously except for the intervention of mechanism now to be described.

The printing-lever I carries a forwardly-projecting pin, k, upon which turns the double-impression pad K. The latter is formed with a central annular groove, k', and on each side

of said groove are a suitable number—for instance five, as shown—of impression-surfaces, those on each side being separated from each other by hollow spaces or depressions, k², the whole being, furthermore, so arranged that the raised impression-surfaces of one side are opposite the depressions of the other side. Fixed to this double-impression pad are two 75 ratchet-wheels, L' L², each having the same number of teeth as there are impression-surfaces on either side of the pad. These two ratchet-wheels are arranged with reference to each other, in a manner similar to the two 80 sides of the impression-pad—that is to say, the teeth of one “break joints” with the teeth of the other.

Upon the front plate of the fixed framing A is mounted an adjustable piece, A', which carries the pivot a² of two pawls, M' M². These pawls are provided with springs m' m², respectively, which tend to hold said pawls out of contact with the teeth of the ratchet-wheels L' L², their upper arms bearing against the 90 fixed stop-pin m³. While both pawls are in this position the printing-lever I may be operated an indefinite number of times, bringing an impression-surface of one side or the other of the impression-pad, according to the position 95 of the latter for the time being, against the corresponding type-wheel J' or J², and effecting an impression from the latter upon the interposed paper strip X.

Supposing the parts to be in the position 100 shown in Fig. 8, the pad being so placed that impressions can be taken from the type-wheel J', when it is now desired to partially revolve the pad K, so as to bring the next following impression-surface of that row which is in the 105 plane of the wheel J² in position to make impressions, while presenting a hollow space to the characters of the wheel J², the escapement-wheel is caused to be arrested at such a point that an arm, N', projecting radially from the 110 arbor B, strikes against and presses outward the inclined end of the upper arm of the pawl M', presenting the lower arm thereof in the path of the ratchet-wheel L², so that as the printing-lever now moves upward a tooth of 115 said wheel L² comes in contact with the lower arm of the pawl M², whereby both ratchet-wheels and the connected impression-pad are turned one step, presenting now an impression-surface against the type-wheel J². A retaining spring-pawl, O, engages now with a tooth 120 of the ratchet-wheel L' and holds the pad firmly against any accidental turning backward. In similar manner, when it is desired to change from impressions from the wheel J² 125 to impressions from the wheel J', the escapement-wheel is arrested in such position as to bring another radial arm, N', on the arbor B in contact with the upper arm of the pawl M', whereby the lower end of the latter, on the 130 elevation of the printing-lever, is brought in contact with a tooth of the ratchet-wheel L', causing the latter and the impression-pad to make a further step in the same direction, the

impression being now taken from the wheel J', and the pawl O engaging with a tooth of the wheel L' to prevent return motion. It will be noticed that each forward step or movement of the parts due to the impact of a tooth of either wheel L' or L² against the end of its pawl M' or M² brings the following tooth of the other wheel into position to be acted upon by its pawl when the latter is operated by its radial arm on the arbor B, while that wheel which has just been turned does not present a tooth to be acted upon by its pawl, even if the latter were pushed inward, the following tooth of that first wheel being only presented after the tooth of the second wheel has, by impact with the pawl of the latter, caused another forward step of the parts, and that being accomplished, the first wheel will again present a tooth in position to be acted upon. It follows from this that mistakes from any accidental cause are not liable to occur, which would be the case if a second step could be made by the impression-pad in consequence of an impact with its pawl of a second tooth of the same wheel that has caused the previous step. In Fig. 8 these parts are shown with the pad in position to print from the type-wheel J'. Fig. 9 shows the same parts with the pawl M² in position to turn the pad on the elevation of the printing-lever, and Fig. 10 shows the parts after such turning has been effected. The retaining-pawl O engages alternately with the teeth of the wheels L' and L², this being evident when it is considered that twice as many steps are necessary to complete a revolution of the impression-pad as there are teeth in either of the wheels L' and L². In order to still further insure that the paper strip X shall not touch a character of that type-wheel which is to be inoperative for the time being, I arrange an arm, R, extending downward between the two type-wheels, J' J². The free end of this arm projects slightly beyond the periphery or surfaces of the characters of the type-wheels into the groove k' of the impression-pad, so that when the latter, and with it the paper strip X, is raised to receive an impression, only that side of the strip X which is supported upon one of the raised impression-surfaces of one side of the pad will come in contact with the corresponding type-wheel, while the other side of the strip X, by coming in contact with the end of the arm R, is slightly deflected into the hollow space k² on the other side of the pad, then presented toward the adjacent character of the other type-wheel, thus positively preventing contact with the corresponding type-wheel of that side of the strip which is to remain blank. This arm R may be fixed upon any suitable support. I have shown it as being attached to the bridge which forms the front bearing of the escapement-arbor B. In order to properly regulate the degree to which the end of this arm R shall project beyond the surfaces of the characters of the type-wheels, I fasten it by means of a clamping-screw, r, and a set-screw, r', serving to slightly

change the inclination as desired. The strip of paper to be printed passes through a slotted post, P, the end of which is screw-threaded 70 and carries a nut, P', which may be screwed inward or outward, according to the width of the paper strip. This is an important feature, inasmuch as it forms a ready adjustment and constitutes an efficient guide, the edges of the 75 paper passing one along the inner end of the slot and the other along the inner face of the nut P', whereby the motion of the paper in a straight line is insured.

Q is a feed-roller, of rubber or other suitable material, carrying in or near its central transverse plane a serrated metal disk, q, upon which presses a spring-mounted roller, q', the paper strip passing between the rollers Q, q, and q', as shown. The feed motion is obtained by means of a ratchet-wheel, q², and a spring-pawl, q³, pivoted to the end of the printing-lever I, so as to partially turn the ratchet q², and consequently the roller Q q, at every return or downward motion of the printing-lever. Those spaces of the type-wheels which will come opposite the impression-surfaces of the pad K when one or the other of the arms N' or N² has thrown in its respective pawl M' or M², for partially turning the pad, 95 may be either blank spaces, or they may contain simply a point, which will then be printed, as the first character of the series in the upper or lower row, as shown in Fig. 13.

Many modifications may be made in the details without departing from the principles of the invention. Certain parts may be used without the others. One modification which readily suggests itself, and which I propose to employ in some cases, is to place the pawls 100 M' M² on the side opposite to that shown in the drawings, their lower ends being in that case provided with hooks to engage with the teeth of the ratchet-wheels L' L². It is evident that the partial revolution of the pad K 110 in this case will take place during the downward motion of the printing-lever I. This modification is illustrated in Fig. 14. I can work the instrument without the use of the split circuit, as described, arranging all the 115 magnets C, D, and H in series; but in that case a more powerful current will be required to obtain a reliable operation.

I claim as my invention—

1. A permanent horseshoe-magnet having 120 pivoted to its poles a double armature, as described, in combination with two electro-magnets co-operating with said armature, an escapement-wheel, means for actuating said escapement-wheel, and means for controlling 125 it, carried on said double armature, substantially as herein specified.

2. In a printing-telegraph instrument, the combination, with one or more escapement-magnets, of a printing-magnet arranged in 130 multiple arc with reference to the former, and with a circuit-breaking device, as 1, controlled by the printing-magnet, and arranged to automatically cut out the escapement magnet or

magnets from the circuit, substantially as herein specified.

3. In a printing-telegraph instrument having an escapement magnet or magnets and a printing-magnet arranged in multiple arc, the combination, with a printing-lever and a circuit-breaking device, as 1, actuated thereby, of a spring, as I', for returning said lever after its operation, and of a suitable stop for said 10 spring, to allow the operative movement of the printing-lever to begin without the resistance of said spring, substantially as and for the purposes herein specified.

4. In a printing-telegraph instrument having two type-wheels upon a common shaft and means for actuating the same, an impression-pad having two series of alternating raised impression-surfaces and depressions, in combination with ratchet-wheels, as L' L², pawls 15 M' M², for revolving the same at will with a step-by step motion, and with means, as O, for preventing any return motion, substantially as and for the purposes herein specified.

5. In a printing-telegraph instrument, the combination of two type-wheels mounted upon a common shaft, suitable means for revolving said shaft and arresting it in desired positions, radial arms N' N², projecting from said shaft, 20 25

and double-armed spring-pawls M' M², in combination with two ratchet-wheels, L' L², double-impression pad K k², carrying said wheels, and revolving upon a suitable pin projecting from the printing-lever I, and with suitable means for elevating and depressing the latter, all arranged and adapted to operate substantially as and for the purposes herein set forth. 30 35

6. In a printing-telegraph instrument, the double-printing pad K, having a central groove, k', and on each side thereof alternating raised impression-surfaces and depressions, and capable of being operated with reference to two type-wheels, in the manner herein set forth, in combination with an arm, R, projecting downward between said type-wheels and slightly beyond the surfaces of 40 45 their characters, substantially as and for the purposes herein specified.

In testimony whereof I have hereunto set my hand, at New York, this 10th day of May, 1883, in the presence of two subscribing witnesses. 50

ALOYS WIRSCHING.
